UNITED STATES PATENT OFFICE.

MARY GEBHARDT, OF SCOTIA, NEBRASKA.

CORSET TRUSS.

Application filed August 22, 1921. Serial No. 494,174.

To all whom it may concern:

Be it known that I, MARY GEBHARDT, a citizen of the United States, residing at Scotia, in the county of Greeley and State 5 of Nebraska, have invented certain new and useful Improvements in a Corset Truss; and I do declare the following to be a full, clear, and exact description of the invention, such as will enable others skilled in the art 10 to which it appertains to make and use the same.

This invention relates to an improved corset truss and one object of the invention is to provide a truss of a construction similar 15 to a corset and which will serve not only to brace and support the back and abdomen, but will further serve as a truss for persons having a rupture.

Another object of the invention is to provide 20 a corset truss having a construction which will permit the corset fitting properly about the body and permit of it being drawn to the desired tightness so that the abdomen may be well supported and proper pressure 25 applied to a rupture.

Another object of the invention is to so construct this corset truss that the upper portion and lower portion may be independently adjusted and thus permit of the 30 proper pressure being applied where desired.

Another object of the invention is to provide 35 a corset truss in which the forward sections may be connected with the rear section and extended in divergent relation to the same so that when in place the corset truss will fit properly and be comfortable to wear.

This invention is illustrated in the accompanying drawing wherein a corset truss of 40 the improved construction is shown laid out flat.

This corset truss is provided with a rear section 1 which is rectangular in shape and formed of fabric such as is usually used in 45 constructing corsets. A bracing stay 2 is embedded in the rear section and extends longitudinally thereof from a point adjacent the lower edge to a point above the middle as shown. The rear section will thus be 50 braced and prevented from having a tendency to crumple when the truss is in use. The forward sections are of a duplicate construction and each is provided with a forward portion 3 and a rear portion 4. These 55 front sections extend in diverging relation to the rear section and are connected with

the rear section by fabric strips 5 positioned between and connected with the rear section 1 and rear or side portions 4 of the front sections. The forward and rear portions 3 and 4 of each front section are provided with eyes for receiving the upper and lower laces 6 and 7. It will thus be seen that the upper and lower portions of the forward and rear portions 3 and 4 are adjustably 60 connected by separate laces so that the upper and lower portions of the truss may be independently adjusted and pressure applied where desired. Each of the forward portions 3 is further provided at its lower end 65 with a V-shaped cutout 8 and laces 9 so that the lower end portions of the front sections may be drawn in transversely to extend beneath and support the abdomen. The free 70 end portions of the front sections are to be releasably connected and in order to do so, there has been provided buttons 10 and button-holes 11. While the present illustration shows buttons and button-holes for releasably securing the corset truss at the front, it 75 is to be understood that any suitable releasable fasteners could be provided. As previously stated, the truss is to be used for applying pressure to a rupture and in order to do so there has been provided a rupture pad 80 12 which is secured against the inner face of one of the front portions 3. This rupture pad extends beyond the edge of the front section to which it is attached and has its free end portion provided with buttons 13 85 for passing through the button-holes 14 of the forward portion of the second front section. It will thus be seen that when the device is in use, the pad will be positioned against the inner face of the corset truss and 90 will be securely held in the proper position for applying pressure to the rupture when 95 the laces are tightened.

When this device is in use, it will be passed about the waist and the buttons 13 100 passed through the button-holes 14. The buttons 10 will then be passed through the button-holes 11 to fasten the corset at the front and the device will be secured about the body of the wearer. After the corset 105 truss is in place, the laces will be tightened to apply the proper pressure. Hose supporters 15 are provided of the usual construction and are releasably held in place by safety pins or other similar releasable 110 fasteners 16 so that these hose supporters can be removed if it is desired to wear the

truss at all times. There has also been provided supporting tabs 17 of a usual construction, one of which will be applied to the lower end portion of the rear section 1 5 and one of which will be applied to each of the forward portions 3 of the front section.

There has thus been provided a corset truss which will serve as a brace and support for the back and abdomen and which will 10 also serve as a rupture truss. It is to be understood that when manufacturing, the rupture pad 12 may be left separate and attached when purchased so that it will be applied properly to the rupture and the button-holes 14 then provided at the proper 15 points for receiving the buttons 13.

I claim:

1. A corset truss comprising a back section, front sections, flexible means connecting the front and back sections with the front sections extending downwardly in diverging relation to the back section, means for releasably connecting the free ends of the front sections, a rupture pad connected 25 with the free end portion of one of said front sections, and means for releasably connecting the pad with the second front section with the pad positioned against the inner face of the second front section.
2. A corset truss comprising a back sec- 30

tion, front sections, bands connecting the front sections with the back sections, each front section having separate forward and rear portions, laces adjustably connecting the upper and lower end portions of said 35 forward and rear portions, means for transversely contracting the lower ends of said forward portions to draw the same inwardly beneath the abdomen, means for releasably connecting the forward portions at the 40 front, a rupture pad connected with one of said forward portions and extending beyond the forward edge thereof, and means for releasably connecting the free end of said rupture pad with the second forward por- 45

3. A corset truss comprising sections having free front edges, means for releasably connecting the free edges of said sections, a 50 rupture pad of one piece connected with one section adjacent its front edge and extending beyond the free edge thereof, and means for releasably connecting the free end of the 55 pad with the second section adjacent the front edge thereof with the pad positioned against the inner face of the second section.

In testimony whereof I have hereunto set my hand.

MARY GEBHARDT.
